Application January 10, 1951, Serial No. 205,347

9 Claims. (Cl. 181—59)

1

This invention relates to an exhaust gas silencer and scrubber. In particular, the invention relates to an exhaust gas silencer adapted to reduce to a minimum the noise caused by the exhaust of an internal combustion engine and which at the same time minimizes back pressure on the engine.

The performance of exhaust silencers or mufflers heretofore employed has been a compromise between a maximum acceptable noise level and a minimum acceptable back pressure. The advent of high powered, high speed internal combustion engines has aggravated the exhaust noise problem; yet, no silencers have been afforded which eliminate or reduce such noise to an unobjectionable degree and at the same time cause negligible back pressure in the combustion engine.

The exhaust from an internal combustion engine is in effect a continuous series of high pressure, high temperature and high velocity shock waves of gas, which in order to eliminate the objectionable noise associated with the discharge of such gas stream must be converted into a low pressure, relatively cool, low velocity gas stream as it is being discharged from the exhaust system. The reduction of the noise factor in exhaust discharge can be accomplished by cooling, wave tuning, controlled turbulence, wave scraping, cushioning and swirling of the exhaust stream. However, heretofore the silencers that have been known to the industry have employed only two, or at the most three, of such expedients.

It is, therefore, one of the objects of this invention to provide an exhaust silencer which will reduce to a minimum the velocity, temperature and pressure of the exhaust gas stream being discharged from an internal combustion engine. To the end that this general objective may be attained, it is the purpose of this invention to provide a silencer in which an exhaust gas stream may be cooled to a low temperature whereby the pressure and the resultant velocity of the stream may be reduced, wherein tuning of the shock waves is achieved, wherein the turbulence of the gas stream is controlled, and wherein provision is made for wave scraping and cushioning as the exhaust gases pass through the silencer. A silencer is thereby provided in which substantially all of the known processes are employed for reducing the ultimate noise caused by the normal discharge of the exhaust stream into the open atmosphere.

It is a specific object of the invention to obtain a maximum cooling of the gases as they pass through the silencer. This objective is at-

2

tained by designing the silencer in such manner as to cause the gas passing therethrough to follow a relatively long, outer, air cooled, peripheral wall of the silencing unit where maximum cooling may be attained.

It is a further specific object of the invention to provide for wave tuning of the exhaust gases as they pass through the silencer. This objective is attained by incorporating in the silencer one or more cushioning chambers or wave traps which absorb and store portions of the peak pressure gases until the peak of the shock wave passes and then release such stored portions during the passage of the low pressure gases through the area. This device serves to smooth the pressure differential between the high and low portions of the shock wave.

It is a further specific object of the invention to provide a gas passage through the silencer which is of relatively large area, so that in the passage of the exhaust gases through such passages the pressure of the stream will be dissipated and velocity of the stream will be decreased.

It is a further specific object of the invention to provide a silencer in which there is only unidirectional flow of the gases so as to avoid restrictive turbulence which creates back pressure.

It is a further object of the invention to provide means for dampening the shock wave and for causing non-restrictive or controlled turbulence in the flow of the gas stream through the silencer unit. This objective is achieved by providing cushioning chambers in the silencer unit in which peak wave pressure of the gas stream is dissipated.

It is a further object of the invention to provide a gas entrance chamber which is of large volume and in which the gases are given a vortex movement, thereby avoiding restriction to the gas stream flow, while at the same time subjecting the stream to maximum cooling by contact with outer heat dissipating surfaces of the silencer.

It is still a further object of the invention to provide a silencer having therein a suitable chamber for holding an exhaust gas treating substance in such manner as to insure the intimate contact of the gas stream and the treating substance, so that the exhaust gas may be deodorized and the noxious constituents thereof may be neutralized before the gas is discharged into the open atmosphere.

These and other objectives of the invention will appear as the detailed description of the invention proceeds when read in light of the draw-

ings forming a part of this application, and in which drawings:

Figure 1 is a side elevational view of the silencer with portions broken away to show underlying structure; and

Figure 2 is a cross-sectional view of the silencer on line 2-2 of Figure 1.

The silencer is a generally elongated casing having therein a plurality of interconnecting chambers constituting a single, continuous path for engine exhaust gases on their way to the atmosphere. One end of the silencer casing is provided with a flange 10 which serves to separate or seal off the several chambers of the silencer, and serves also as a means through which an exhaust pipe 12 may be connected to the silencer for conducting high pressure exhaust gases thereto. The exhaust pipe 12 discharges into a generally circular inlet chamber 14, which extends throughout the axial length of the silencer. The wall of the inlet chamber 14 is exposed to the atmosphere throughout its major diameter, and thereby provides for a maximum cooling of the gases received therein. Because of the generally circular cross-sectional contour of the inlet chamber, coupled with a tangential outlet therefrom there is immediately imparted to the incoming gases a swirling motion which causes the hot, high pressure, high velocity gases to contact the outer, air-cooled, peripheral wall of the chamber which divests these gases of much of their heat by conduction through the atmospherically cooled wall of the inlet chamber. From the inlet chamber 14 the partially cooled gases enter one or more cooling or diffusing wings which are in the shape of a hollow, axially disposed fin extending generally radially in respect to the longitudinal center line of the silencer. One such wing is provided by a pair of spaced side walls joined by an end wall. These walls are in contact with the atmosphere and provide a long cooling path for the exhaust gases in contact therewith.

Specifically, the entrance chamber 14 discharges into a cooling and diffusing wing 16, by way of a tangentially disposed throat 18, which extends along the length of the silencer structure. Thus, the vertically moving gases within the entrance chamber 14 move without substantial turbulence from the entrance chamber 14, through the throat 18 and into the cooling and diffusing wing 16.

For the purpose of insuring contact of a maximum amount of gas with the outer atmospherically cooled walls of the wing 16, there is provided in the wing a guide baffle which serves this purpose. Accordingly, there is provided a dividing baffle 20 which is affixed to the wall 21 of the silencer discharge chamber and in such position as to lie substantially in the geometric center of the cooling and diffusing wing 16 and in a substantially radial position in respect to the center line of the silencer. The dividing baffle 20 is a solid plate, preferably of imperforate sheet metal, which extends throughout the axial length of the silencer.

Within the wing 16 is provided a shock wave scraping and cushioning structure which is designed to modify the nature of the gas stream as it passes through the silencer. Disposed on each side of the baffle 20, and in a somewhat angular relation thereto, are a pair of perforated primary baffle or cushion plates 22 and 24. Between the primary baffle plate 22 and the solid baffle plate 20 is a secondary perforated baffle or cushion

plate 26, and between the primary baffle 24 and the solid baffle plate 20 is a secondary perforated baffle or cushion plate 28. By this structure there is provided on each side of the solid baffle plate

5 26 a primary and a secondary pressure chamber, i. e., a primary pressure chamber is formed between the plates 22 and 26 on the one hand and between the plates 24 and 28 on the other hand. A secondary pressure chamber is formed between the plates 20 and 26 on the one hand, and between the plates 20 and 28 on the other hand.

The wing structure 16 has a flattened portion 30 which, together with the outer converged ends of the respective baffles, provides a channel 15 through which gases passing about the wing structure may flow from the inlet side of the structure to the discharge side of the structure. A perforated baffle strip 32 is disposed along the wall 30 and in spaced relation thereto, whereby 20 a further cushioning chamber is provided at the area in which the exhaust gases pass from the entrance side of the wing to the discharge side of the wing.

The perforations in the plates 22 and 24 comprise substantially one-half the entire area of these plates, whereas the perforations in the plates 26 and 28 constitute only thirty per cent of the area of these latter plates.

As the exhaust gas passes from the entrance 30 chamber 14, through the discharge throat 18, it flows along the surface of the shell constituting the wing 16 and the primary cushioning plate 22. During a pulsation of high pressure, a small portion 35 of the gas in its passage enters the primary cushioning chamber formed between the cushion plates 22 and 26. This absorbs and stores some of the energy of the high pressure pulsations and permits the remaining portion of the gas to proceed in its passage through the cooling and diffusing wing. The gas which passes on in normal course is scraped by the perforations in the cushion plate 22, and this imparts to such gas a rolling 40 action in the direction of flow. The rolling action of the passing gas causes a maximum of hot gas to come into contact with the outer shell of the cooling and diffusing wing 16, thus providing a maximum cooling effect.

After the partially reduced pressure wave of 50 flowing gas stream has passed on, the entrained portion of the pulse charge in the primary cushioning chamber between cushion plates 22 and 26 re-emerges and combines with the low pressure stream then passing that point.

The secondary cushion chamber formed between the cushion plate 26 and the baffle plate 20 delays the return flow of the entrapped gases in the cushioning chambers and thereby there is provided a modified tuned wave arrangement which functions substantially in proportion 60 of the frequency of the shock wave pulsations and acts in effect to level the peaks and valleys of the percussions caused by the engine exhaust.

Inasmuch as the cooling and diffusing wing has a primary and a secondary wave trap disposed on each side of the dividing baffle 20, the dampening process applied to the exhaust stream is performed twice as the exhaust stream passes through the cooling and diffusing wing 16. As the gas stream passes along the discharge side 70 of the cooling and diffusing wing, the dampening and cooling process is precisely the same as that effected on the entrance side of the wing with the exception that the pressure and temperatures on the discharge side are lower by virtue 75 of the treatment received by the gases along

the entrance side of the wing. The gases from the discharge side of the cooling and diffusing wing 16 may be discharged into a generally axially disposed discharge chamber 34 which is closed at one end by the end flange 10, but for which discharge to the atmosphere is provided through an opposite end flange 36. Provision is made for attaching an exhaust pipe 38 to the end flange 36, whereby gases treated within the silencer may be discharged to the atmosphere.

In its preferred form the silencer herein embodies a plurality of wings such as the wing 16, each having a baffle and a plurality of baffle or cushion plates, such as the plates 22, 24, 26 and 28. Accordingly, in the drawing there is shown a structure in which four such cooling and diffusing wings are provided. When a plurality of such cooling and diffusing wings are employed, each wing following the entrance chamber 14 discharges into a succeeding wing. Thus, in the illustrated embodiment of the invention, the wing 16 is adapted to discharge its gases into a wing 37, and the wing 37 is designed to discharge the stream of exhaust gases into a wing 39. Finally, the wing 39 discharges its gases into a wing 40 which is provided with an axially disposed passage forming a discharge throat 42, through which the exhaust gases are adapted to pass into the outlet chamber 34.

It will be appreciated that but for the outlet throat 42 the wings 37, 39 and 40 are identical with the first cooling and diffusing wing 16. Each of these wings constitute an axially disposed chamber of hollow, fin-like form in which the cushioning chambers are provided by the respective baffle or cushioning plates referred to in connection with the initial cooling and diffusing wing 16.

The discharge throat 42 is tangentially disposed with respect to the axis of the discharge chamber 34, so that the low pressure gas stream enters the chamber in a whirling stream which finally tends to dissipate the last vestige of shock wave pressure therein. In this regard it is to be noted that the cooling and wave tuning action in each of the cooling and diffusing wings successively cools and dampens the pulsating gas stream as it passes through the silencer, so that by the time the exhaust gases have reached the discharge chamber 34 they are substantially cooled and at such low pressure that they may be discharged through the exhaust pipe 38 without objectionable noise. In this regard it is to be noted that the baffles 32 carried by the cooling and diffusing wings serve substantially to reduce resonance in the silencer shell so that the overall operation of the silencing device is so effective as to reduce the exhaust noises to almost an inaudible minimum.

In order that the exhaust gases may be subject to a scrubbing action for the removal of odors and noxious gas constituents, there is provided along the line of gas flow a reservoir 42 in which a suitable reagent may be placed by which the obnoxious characteristics of exhaust gas may be neutralized.

In the specific embodiment of the invention herein illustrated, the reservoir 42 is provided at the junction of two of the cooling and diffusing wings. As illustrated in the drawings, it is located between the wings 37 and 39, and it is formed by bending the outer shell of the silencer to provide an outwardly extending trough in which the reagent may be deposited. This trough extends axially along the length of the

silencer so that the entire width of the gas stream may be subject to its influence. A perforated plate 44 may constitute a closure for the reservoir, and in connection therewith a downwardly extending baffle 46 is provided for insuring adequate contact between the flowing gas stream and the reagent in the reservoir.

The invention herein has been described with reference to a specific form thereof, but from the 10 exposition of the principles embodied, it will be possible for those skilled in the art to vary the specific structure; and it is the purpose of this application to cover within the scope of the claims thereof such modifications as may be suggested by the specification.

What is claimed is :

1. An exhaust silencer for internal combustion engines and the like, comprising walls forming an elongate entrance chamber of predetermined length and having at one end thereof an entrance opening for a stream of exhaust gases to be silenced, walls forming a discharge chamber disposed in substantially parallel relation to said entrance chamber, said entrance and discharge chambers being substantially coextensive in the direction of said predetermined length, and said discharge chamber having an exit opening for the flow of gases from said silencer at the end thereof opposite that end of the silencer at which gases are adapted to be supplied to said entrance chamber, a casing rigidly mounted with respect to all said walls and including a pair of spaced walls and a center baffle jointly forming a gas cooling wing disposed 20 in substantially radial relation in respect to said discharge chamber and substantially coextensive therewith in the direction of said predetermined length, said center baffle being mounted on a wall forming said discharge chamber, a passage formed between one of said pair of spaced walls and said center baffle and coextensive with said predetermined length from said entrance chamber to said cooling wing on one side of the center baffle thereof, and a passage 25 formed by some of said walls and said casing and coextensive with said predetermined length and extending from that portion of said cooling wing on the other side of the center baffle thereof to said discharge chamber.
2. An exhaust silencer in accordance with claim 1, wherein said passage from said entrance chamber to said cooling wing communicates tangentially with said entrance chamber.
3. An exhaust silencer in accordance with claim 1, wherein said passage from said cooling wing to said discharge chamber communicates tangentially with said discharge chamber.
4. An exhaust silencer for internal combustion engines and the like, comprising walls forming an elongate entrance chamber of predetermined length and having at one end thereof an entrance opening for a stream of exhaust gases to be silenced, walls forming a discharge chamber disposed in substantially parallel relation to said entrance chamber, said entrance and discharge chambers being substantially coextensive in the direction of said predetermined length, and said discharge chamber having an exit opening for the flow of gases from said silencer at the end thereof opposite that end of the silencer at which gases are adapted to be supplied to said entrance chamber, a casing rigidly mounted with respect to all said walls and forming therewith a plurality of cooling wings each substantially coextensive with said predetermined length and all

disposed radially of said discharge chamber, each of said cooling wings being formed by a pair of spaced walls forming a part of said casing and joined together at their radial outer edges, a center baffle secured to said walls forming said discharge chamber and cooperating with the walls of said casing in providing each of said wings respectively, a passage formed between one of said pair of spaced walls and the center baffle aforesaid jointly forming a first of said cooling wings and coextensive with said predetermined length from said entrance chamber to the first of said cooling wings on one side of the center baffle thereof, a passage formed by some of said walls and said casing and coextensive with said predetermined length and extending from that portion of a last of said cooling wings on the other side of the center baffle thereof to said discharge chamber, and passage means formed by portions of said discharge chamber forming walls and said casing and serially connecting the adjacent side portions of each of said cooling wings from said first cooling wing to said last cooling wing, so as to provide a continuous passage for gases extending in series from said entrance chamber through all said cooling wings to said discharge chamber.

5. An exhaust silencer for internal combustion engines and the like, comprising walls forming an elongate entrance chamber of predetermined length and having at one end thereof an entrance opening for a stream of exhaust gases to be silenced, walls forming a discharge chamber disposed in substantially parallel relation to said entrance chamber, said entrance and discharge chambers being substantially coextensive in the direction of said predetermined length, and said discharge chamber having an exit opening for the flow of gases from said silencer at the end thereof opposite that end of the silencer at which gases are adapted to be supplied to said entrance chamber, a casing rigidly mounted with respect to all said walls and including a pair of spaced walls and a center baffle jointly forming a gas cooling wing disposed in substantially radial relation in respect to said discharge chamber and substantially coextensive therewith in the direction of said predetermined length, said center baffle being mounted on a wall forming said discharge chamber, said spaced walls and said center baffle comprising walls bounding a through passage for gases through said wing, a perforated wall in said wing secured to and cooperating with a portion of the walls bounding the through passage thereof to define a pressure cushioning chamber in said wing which is completely closed to said through passage except for the perforations of said perforated wall, so as to leave in said wing a through passage for gases uninterrupted by said perforated wall, while providing for the flow of gases into and out of said pressure cushioning chamber through the perforations of said perforated wall, a passage formed between one of said pair of spaced walls and said center baffle and coextensive with said predetermined length from said entrance chamber to said cooling wing on one side of the center baffle thereof, and a passage formed by some of said walls and said casing and coextensive with said predetermined length and extending from that portion of said cooling wing on the other side of the center baffle thereof to said discharge chamber.

6. An exhaust silencer for internal combustion engines and the like, comprising walls forming

10 an elongate entrance chamber of predetermined length and having at one end thereof an entrance opening for a stream of exhaust gases to be silenced, walls forming a discharge chamber disposed in substantially parallel relation to said entrance chamber, said entrance and discharge chambers being substantially coextensive in the direction of said predetermined length, and said discharge chamber having an exit opening for the flow of gases from said silencer at the end thereof opposite that end of the silencer at which gases are adapted to be supplied to said entrance chamber, a casing rigidly mounted with respect to all said walls and including a pair of spaced walls and a center baffle jointly forming a gas cooling wing disposed in substantially radial relation in respect to said discharge chamber and substantially coextensive therewith in the direction of said predetermined length, said center baffle being secured to one of said walls forming said discharge chamber, said spaced walls and said center baffle comprising walls bounding a through passage for gases through said wing, a V-shaped perforated wall disposed with the apex of the V along and surrounding the edge of said center baffle remote from said discharge chamber with the edge portions of said perforated wall parallel to the apex of the V secured to said walls providing said discharge chamber, a second V-shaped perforated wall similar to the first-named perforated wall but with a greater included dihedral angle at the apex of the V and disposed and secured similarly to and outside said first-named perforated wall, said perforated walls and said center baffle providing, with parts of said walls providing said discharge chamber, two primary and two secondary pressure cushioning chambers in said wing, so as to leave in said wing a through passage for gases uninterrupted by said perforated walls, while providing for the flow of gases into and out of said pressure cushioning chambers solely through the perforations of said perforated walls, a passage formed between one of said pair of spaced walls and said center baffle and coextensive with said predetermined length from said entrance chamber to that portion of said cooling wing on one side of the center baffle thereof, and a passage formed by some of said walls and said casing and coextensive with said predetermined length and extending from that portion of said cooling wing on the other side of the center baffle thereof to said discharge chamber.

15 7. An exhaust silencer in accordance with claim 6, wherein the perforations of said first named perforated wall occupy about 30% of the area thereof, and wherein the perforations of the second named perforated wall occupy about 50% of the area thereof.

20 8. An exhaust silencer in accordance with claim 1, comprising in addition, a receptacle for a liquid gas-treating reagent communicating above the surface of the liquid therein with one of said passages, and means tending to cause gases to flow past and in contact with liquid in said receptacle.

25 9. An exhaust silencer in accordance with claim 1, wherein a plurality of gas cooling wings, each as aforesaid, are provided between said entrance chamber and said discharge chamber, passages for gases connecting said wings in series, and comprising in addition, a receptacle for a liquid gas-treating reagent communicating above the surface of the liquid therein with one of said 30 passages, and means tending to cause gases to

flow past and in contact with liquid in said receptacle, said receptacle being disposed below one of the last named passages connecting similar gas cooling wings when said silencer is positioned with its dimension along said predetermined length substantially horizontal, said receptacle communicating with said one last named passage through a perforated wall, and wherein said means tending to cause gases to flow in contact with liquid in said receptacle comprises a deflecting baffle opposite said perforated wall tending to deflect gases through said perforated wall and into contact with the surface of liquid in said receptacle.
